INDIVIDUAL CIGAR BOX

Hyman Jacobstein, New Rochelle, N. Y.

Application June 27, 1936, Serial No. 87,780

13 Claims. (Cl. 131—11)

This invention relates to an improved cigar box and one object of the invention is the production of a cigar box of such construction that cigars may be individually boxed and sold from a counter or humidor and the supply renewed when the humidor is empty instead of displaying the cigars in a box constructed to hold a large number of cigars and discarding the box when the cigars have all been sold.

It is another object of the invention to so form the improved cigar box that the individual cigars will be entirely enclosed and protected from exposure to air, light, and other atmospheric conditions that are injurious to cigars, each box having a revenue stamp applied thereto and being of such construction that the box and the stamp will be destroyed when the cigar is removed and thus prevent reuse of the box or the stamp.

Another object of the invention is to so construct the box that when a cigar is enclosed therein, its normal moisture will be preserved and thus reduce to a minimum the necessity of supplying artificial humidification to a counter or humidifier from which the cigars are sold.

Another important object of the invention is to so form the box that one end thereof will have a bevelled surface. Therefore, when one or more cigars are placed in a coat pocket, they will not only be protected against crushing but end portions of the boxed cigars which project upwardly from the pocket will be attractive in appearance and disposed close against the coat so that they will not be liable to be caught or struck against a person's arm or any other object and broken or dislodged from the pocket.

Still another object of the invention is the provision of a cigar box in which the cigar may be entirely enclosed where it will be shielded from contact with a person's hand when picked up, thereby permitting the cigars to be individually removed from a humidor case or box by a cigar dealer when making a sale instead of removing a box containing a number of cigars, as now required by sanitary regulations of public health departments and regulations of the Bureau of Internal Revenue.

It is another object of the invention to so form the box that the cigar will be enclosed in cedar and also in waxed paper and metal foil, thus subjecting the boxed cigar to the aroma of the cedar and also preventing escape of aroma from the cigar and also preventing drying of the cigar.

Another object of the invention is to provide the improved cigar box with improved means

for splitting the same longitudinally when a cigar is to be removed, thereby permitting easy removal of the cigar and at the same time assuring destruction of the box and the revenue stamp applied to the box.

A still further object of the invention is the production of a cigar box consisting of companion elements all of which may be stamped from sheet material and easily assembled, thus reducing the cost of the box to a minimum, and also permitting mass production and the packing of cigars in the boxes by machinery.

With these and numerous other objects in view, my invention consists in the novel features of construction, combination and arrangement of parts as will be hereinafter referred to and more particularly pointed out in the specification and claims.

The invention is illustrated in the accompanying drawings wherein:

Figure 1 is a view of the completed box with a cigar therein indicated by dotted lines;

Figure 2 is a view showing the cigar box of Figure 1 in bottom plan;

Figure 3 is a view of one end of the box looking in the direction of the arrow A in Figure 1;

Figure 4 is a view of the other end of the box looking in the direction of the arrow B in Figure 1;

Figure 5 is a perspective view of the box as it appears before enclosing a cigar therein;

Figure 6 is a similar view illustrating the first step when enclosing a cigar in the box;

Figure 7 is a view similar to Figure 1, illustrating the manner in which the box is opened for removal of a cigar;

Figure 8 is a view of the blank from which one portion of the box is formed;

Figure 9 is a view of the blank forming the opener and a layer of the bottom of the box;

Figure 10 is a view of another blank forming a portion of the box;

Figure 11 is a view of blanks from which sealing elements are formed;

Figure 12 is a top plan view of the box formed from the elements shown in Figures 8 through 11 when assembled;

Figure 13 is a sectional view taken along the line 13—13 of Figure 11;

Figure 14 is a sectional view taken along the line 14—14 of Figure 1; and

Figure 15 is a perspective view illustrating a modified construction.

This improved cigar box has been illustrated of the proper dimensions to enclose a single cigar,

but it is to be understood that it may be of increased size if two or more cigars are to be housed therein. It consists briefly of an inner section or main box 1, an outer section or wrapper 2 and an opener 3 by means of which the outer section is to be slit longitudinally when it is desired to open the box and remove a cigar 4 therefrom.

The inner section which forms the body portion of the box consists of a laminated structure having an inner sheet 5 of thin cedar wood and an outer sheet 6 of waxed paper or soft tissue paper. These sheets are subjected to pressure or glued which causes them to closely adhere to each other and are stamped as a unit from large sheets of material. At opposite sides of the inner edge portion of the section 1 are formed tongues 7 which are notched at their junction with the body portion of the section as shown at 8 in order that the tongues may be easily bent upwardly to form end walls for the box and also effect rounded corners for the box. At one end, the inner section is cut straight across as shown at 9, whereas at its other end this section is formed with an edge 10 having the outline of a reversed curve.

The outer section or wrapper preferably consists of an inner sheet 11 of paper and an outer sheet 12 of metal foil. This section 2 is substantially rectangular in shape but has its corners cut off diagonally as shown at 13. At one end, the section 2 is cut to form a recess 14 which is spaced from the inner side edge of the section a distance corresponding to the width of the tongues 7. By this arrangement, the recess will be disposed at one side of the bottom of the box and the free end portion of the blade 15 of the opening 3 may project through the recess as shown in Figures 1 and 2 when the box is fully formed and a cigar housed therein. The opener is preferably formed of cardboard although other flexible materials may be used and consists of the blade 15 and a base portion or strip 16 which extends longitudinally of the blade at one side thereof. This strip corresponds in width to the tongues 7 and near its ends is formed with side notches 17 defining tongues 18 corresponding to the shape and dimensions of the tongues 7 and disposed directly under the same when the strip is disposed between overlapped inner side edge portions of the inner and outer sections and glued thereto. The overlapped and adhesively secured portions of the opener and the two sections 1 and 2 form a bottom for the box which is of multiple thickness and of such stiffness that it will not bend out of shape. Therefore, the bottom of the box will be flat and serve to impart rigidity to the box. Stiff end walls for the box will also be provided when the tongues 7 and 18 and companion portions of the section 2 are bent upwardly between the notches 8 and 17. In view of the fact that the blade of the opener has its wide end portion integrally united to the strip 16 as shown at 19, the blade will be firmly held in its proper position longitudinally of the box with its free end projecting through the passage defined by the recess 14 and when this protruding end of the blade is grasped and pulled upon to draw the blade back upon itself and outwardly through the outer section or wrapper as shown in Figure 7, the blade will be firmly anchored at its wide end and a good cutting action takes place which will cause the blade to easily tear its way through the outer section and split the same longitudinally of the box,

as well as through a seal which secures the inner box in its rolled condition.

When this box is in use, a cigar is placed upon the outer side portion of the inner section 1 and this section rolled as shown in Figure 6 to enclose the cigar, as shown in Figure 14 with the free side edge portion of the inner section engaged between the cigar and the bottom of the box. The tab or seal 20 which has its shank secured under the strip 16 is then drawn upwardly together with the blade 15 which extends across the shank and the gummed portion 20' of the tab glued to the rolled inner section with the blade extending between the tab and the box. The tongues 7 are then bent upwardly to form end walls for the box and the tabs 22 carried by the inner section and projecting from ends thereof are folded inwardly and secured across the bent tongues to hold them in their wall forming positions. The outer section 2 is then folded about the inner section or body-forming portion of the box and the side edge portion of this section which is gummed by having glue applied to it as shown at 23 adhesively secured under the bottom of the box in overlapped relation to the initially secured side edge portion of the outer section or jacket as shown in Figure 14. Therefore, the outer section or jacket will be firmly secured in enclosing relation to the inner section or body of the cigar box and when end portions of the rolled outer section are folded inwardly against the end walls and glued as shown at 24 and 25 in Figures 3 and 4, the cigar will be housed in an individual box which is air tight and serves to prevent the aroma of the cigar from escaping and also prevents air reaching the cigar which would cause it to dry.

The outer surface of the metal foil is marked to provide a label 26 constituting a representation of a cigar band and when the revenue stamp 27 is applied circumferentially of the box, it extends in crossed relation to the blade so that when this blade is drawn outwardly back upon itself to tear its way through the jacket and the tab 20 so that the inner section may be unrolled and the cigar removed, it will also pass through the stamp and destroy the same. By having the edge 10 of the section 1 curved as shown in Figures 5 and 10, this end of the formed box will extend diagonally instead of straight across at right angles to the longitudinal axis of the box. Therefore, when the boxed cigar is placed upright in a coat pocket with the bevelled end of the box uppermost, this end wall of the box will extend outwardly at a downward incline and will be very pleasing in appearance. The angular disposition of this end of the box also serves to prevent the projecting end of the box from being accidentally caught and dislodged from the pocket. A cigar box so constructed affords ventilation, cedarization and humidification. If so desired, the inner section 1 may be formed with perforations 28 distributed throughout its area as shown in Figure 15 so that air confined within the box may circulate through these openings and assist in preserving the freshness and aroma of the cigar. The outer section 2 may also be perforated. While a revenue stamp has been shown applied to the box, it is to be understood that it may be omitted if it is desired to pack a large number of cigars in a box and apply a single stamp to the box as now done.

From the foregoing description of the construction of my improved device, the method of applying the same to use will be readily under-

stood. It will be seen that I have provided a simple, inexpensive and efficient means for carrying out the objects of the invention and while I have particularly described the elements best adapted to perform the functions set forth, it is obvious that various changes in form, proportion and in the minor details of construction may be resorted to, without departing from the spirit or sacrificing any of the principles of the invention.

Having thus described the invention, what is claimed is:

1. A cigar box comprising a cylindrical body formed of sheet material rolled about a cigar and enclosing the same, a jacket formed of sheet material secured along one side under a side edge portion of the first sheet and folded about the body and enclosing the same, and an opener comprising an anchoring element secured between overlapped side edge portions of said sheets and a flexible blade extending longitudinally of the body between the body and the jacket with one end joined to the anchoring element and its other end protruding through an end of the jacket.

2. A cigar box comprising a cylindrical body formed of laminated sheets of cedar and paper rolled from their outer side edges about a cigar and enclosing the same, the said laminated sheets having end tongues forming end walls for the body, a jacket formed of laminated sheets of paper and metal foil united along its inner side edge to the first mentioned laminated sheets and folded about the body and enclosing the same, and an opener comprising an anchoring strip extending longitudinally of the body between the united edge portions of the first and second mentioned laminated sheets and a blade extending longitudinally of said strip at one side thereof with one end joined to the strip and its other end free and protruding from an end of the jacket.

3. A cigar box comprising a cylindrical body formed from a sheet rolled about a cigar and having end tongues bent upwardly and forming end walls for the body, tabs carried by said sheet with portions projecting therefrom and secured in overlapping relation to said tongues to secure the tongues in wall forming positions, a jacket formed from a sheet secured along its inner side edge under the inner side edge portion of the first sheet, an opener comprising an anchoring portion secured between overlapped portions of said sheets and a flexible blade secured at one end to the anchoring portion and extending longitudinally of the anchoring portion at one side thereof, and a tab secured between the anchoring portion and the overlapped portion of the second mentioned sheet and projecting transversely from the first mentioned sheet under said blade, the last mentioned tab being folded upwardly in overlying relation to the the cutter and secured against the first sheet to hold the same rolled and seal the body and hold the blade on edge, the second sheet being folded about the body and the blade and secured with the free end of the blade protruding from an end of the box.

4. A cigar box comprising a body formed of a flexible sheet rolled about a cigar and having side edge portions overlapped under the cigar to provide the body with a bottom of double thickness, end walls for said body, a jacket formed from a sheet of material wrapped about and enclosing said body and having overlapped side edge portions disposed under the overlapped portions of the body, and an opener extending longitudinally

of the body and provided with an anchoring member extending longitudinally of the box between the overlapped portions of the body and the jacket and united to a side of one end of the opener, the other end portion of the opener protruding between the body and one head and through the cooperating end of the jacket, whereby the protruding end of the opener may be grasped and the opener drawn back upon itself and torn through the jacket.

5. A cigar box comprising a cylindrical body formed from a blank of aromatic material folded about a cigar to form a body enclosing the cigar and having heads at its ends, side edge portions of the blank being overlapped but free from each other, a jacket formed from a sheet of air and moisture-proof sheet material folded and secured in enclosing relation to said body, and an opener comprising an anchoring portion disposed between and secured to the jacket and a side edge portion of the body-forming blank, and a flexible blade secured at one end to the anchoring portion and extending longitudinally of the package between the jacket and a side of the body with its free end protruding from an end of the jacket.

6. A cigar box comprising a body enclosing a cigar and unsecured along one side, a jacket of thin material enclosing said body, and an opening device between the jacket and the body consisting of a flexible blade extending longitudinally between the jacket and the unsecured side of the body and having anchoring means at one end secured between the jacket and the bottom of the body, the other end portion of the blade being free and protruding from the jacket to provide a finger hold.

7. A cigar box comprising a body enclosing a cigar, a jacket about said body, and a flat flexible blade between the body and the jacket extending longitudinally thereof, one end of the blade being provided with an anchoring member at a side thereof and the other end of the blade being free and protruding from the jacket to provide a finger hold.

8. A cigar box comprising a body of aromatic material enclosing a cigar, a jacket of thin sheet material about said body, and a flexible blade extending longitudinally between the body and the jacket and having one end portion protruding from the jacket and its other end provided with anchoring means firmly secured between the jacket and the bottom of the body.

9. A cigar box comprising a body of aromatic material enclosing a cigar and unsecured along one side, a jacket of thin sheet material about said body, a flexible blade extending longitudinally between the jacket and the unsecured side of the body, and an anchoring strip connected at one end with said blade and being spaced transversely from the blade and secured between the jacket and the bottom of the body longitudinally thereof to reinforce the same.

10. A cigar box comprising a body enclosing a cigar, a jacket of thin sheet material about said body, a flexible blade for opening the jacket extending longitudinally between the jacket and the body, and anchoring means for the blade secured between the jacket and the body and constituting reinforcing means for the same.

11. A cigar box comprising a cylindrical body enclosing a cigar, a jacket of sheet material enclosing said body, and an opener comprising a flat flexible blade extending longitudinally of the box between the body and jacket for the full

- length of the box, said blade having one end provided with a laterally extending anchoring member and being free from the anchoring member for the remainder of its length and having its other end protruding from an end of the jacket whereby the free end of the blade may be grasped and the blade drawn back upon itself through the jacket to tear the jacket longitudinally and permit removal of the cigar.
- 10 12. A cigar box comprising a cylindrical body formed from a blank of aromatic sheet rolled about a cigar and providing a body unsecured along one side, a jacket formed from a blank of air proof and moisture proof material folded about the body and secured in enclosing and sealing relation thereto, a flat flexible blade extending longitudinally of the box between the jacket and the unsecured side of the body and

tapered towards one end, the said end of the blade protruding from an end of the jacket, and an anchoring member for said blade attached to one side of the larger end of the blade.

13. A cigar box comprising a cylindrical body of aromatic sheet material unsecured along one side and having heads at its ends, one head extending diagonally of the longitudinal axis of the body for the full diameter thereof to provide the body with a bevelled end extending entirely across the same, a jacket of thin air proof and moisture proof sheet material enclosing said body, and an opener extending longitudinally of the box between the jacket and the unsecured side of the body with one end protruding from the bevelled end of the jacket adjacent one side thereof.

HYMAN JACOBSTEIN.
